(57) **CLAIM**

(21) Appl. No.: **29/205,882**

The design of the rear cavity surface design for perimeter weighted iron-type golf club head, substantially as shown in the attached drawings.

(22) Filed: **May 24, 2004**

DESCRIPTION

(51) **LOC (8) Cl. 21-02**

FIG. 1 is a perspective view of the rear cavity surface design for perimeter weighted iron-type golf club head;

(52) **U.S. Cl. D21/759**

FIG. 2 is another perspective view thereof;

(58) **Field of Classification Search** D21/747-751,

FIG. 3 is another perspective view thereof;

D21/759; 473/324-331, 350

FIG. 4 is another perspective view thereof;

See application file for complete search history.

FIG. 5 is another perspective view thereof; and,

(56) **References Cited**

FIG. 6 is another perspective view thereof.
